UNITED STATES PATENT OFFICE.

LOUIS J. URICH, OF ELMHURST, NEW YORK, ASSIGNOR TO C. BRANDES, INC., OF NEW YORK, N. Y., A CORPORATION OF NEW YORK.

DESIGN FOR AN ADVERTISING SUPPORT FOR TELEPHONE HEADSETS.

Application filed September 3, 1924. Serial No. 10,668. Term of patent 14 years.

To all whom it may concern:

Be it known that I, LOUIS J. URICH, a citizen of the United States of America, residing in the city of Elmhurst, county of Queens, and State of New York, have invented a new, original, and ornamental Design for an Advertising Support for Telephone Headsets, of which the following is a specification, reference being had to the accompanying drawing, forming a part thereof.

Figure 1, is a front elevation showing my advertising support for telephone headsets with telephone headset in position thereon; and Figure 2 is a side elevation showing the advertising support.

I claim:

The ornamental design for an advertising support for telephone headsets as shown.

LOUIS J. URICH.
